Primary Examiner — April Rivas(57) **CLAIM**

The ornamental design for an earphone case, as shown and described.

DESCRIPTION

FIG. 1 is a front perspective view of an earphone case, showing our new design;

FIG. 2 is a front view thereof;

FIG. 3 is a back view thereof;

FIG. 4 is a top view thereof;

FIG. 5 is a bottom view thereof;

FIG. 6 is a right side view thereof;

FIG. 7 is a left side view thereof;

FIG. 8 is a back perspective view thereof;

FIG. 9 is a front perspective view thereof, shown in an environmental use; and,

FIG. 10 is a back perspective view thereof, shown in an environmental use.

The broken lines in drawings show portions of the earphone case as well as the environment of the claimed design, and form no part thereof.
